UNITED STATES PATENT OFFICE.

JAMES A. ANDERSON, OF GRAFTON, WEST VIRGINIA.

DRIVING-BOX, SHOE, AND WEDGE FOR LOCOMOTIVES.

1,283,616.

Specification of Letters Patent.

Patented Nov. 5, 1918.

Application filed April 27, 1918. Serial No. 231,074.

To all whom it may concern:

Be it known that I, JAMES A. ANDERSON, a citizen of the United States, residing at Grafton, in the county of Taylor and State 5 of West Virginia, have invented certain new and useful Improvements in Driving-Boxes, Shoes, and Wedges for Locomotives, of which the following is a specification.

This invention relates to the driving boxes 10 of locomotives, and its object is to provide a box and a retaining means therefor so constructed that removal of the box may be readily effected without removing the wheels from the jaws of the frame of a locomotive. 15 The object stated is attained by means of a novel combination and arrangement of parts to be hereinafter described and claimed, and in order that the same may be better understood, reference is had to the 20 accompanying drawing forming a part of this specification.

In the drawing—

Figure 1 is a plan view of the box and the parts associated therewith, with the pedestal 25 jaws of the locomotive frame in section on the line 1—1 of Fig. 2, and Fig. 2 is an elevation of the structure, the driving wheel being removed.

Referring specifically to the drawing, 5 30 denotes the pedestal jaws of a locomotive frame of standard type in which seats the driving box 6 through which the journal end of the driving axle 7, carrying the driving wheel 8, passes. Between the opposite 35 faces of the jaws, and the respective ends of the box are interposed the usual wedge 9 and the shoe 10, and the box is fitted with a crown brass 11 shown dotted in Fig. 2.

The box 6 has outstanding end flanges 12 40 on the hub side, the opposite side being devoid of flanges. On the outer end of the wedge 9 is a laterally presented, outturned flange 13, and the corresponding end of the shoe 10 has a similar flange 14. The inner 45 end of the wedge has a lateral, inturned flange 15, and the corresponding end of the shoe has a similar flange 16. The flanges 13 and 14 seat on the outer side of the jaws 5, and the flanges 15 and 16 seat against the 50 rear face or inner end of the box 6. The flanges 12 seat against the flanged outer ends of the wedge and the shoe.

By the flanged construction of the box 6, the wedge 9 and the shoe 10, the box is 55 securely held in place between the jaws 5,

the wedge and the shoe each having three bearing points. In the event of the inner flanges of the wedge and the shoe being broken, the box would still be held in position.

It will be noted that the width of the flanged end of the box 6 is not greater than the distance between the jaws 5, and hence, the box can be slipped inward from between the jaws after the wedge and the shoe are 60 removed. It is therefore possible to remove the box for repairs to the crown brass, or end play, without the necessity of removing the wheels from between the jaws of the frames. The box can be put in place, or 65 removed, by simply taking the weight off the same, without removing the wheels. Another important feature of the design of the wedge and the shoe is, that in case of excessive clearance between the box and 70 the wheel hub, the same can be eliminated by fastening a liner 17 to the flanged end of the shoe and wedge, provided, of course, if the end play liner or brass is still in good 75 condition. The single flanged box, with 80 the double flanged, or Z-shaped wedge and shoe, permit ready repairs to the box, the crown brasses, and end play brasses, and end play clearance can be reduced by the liner shown without removing the wheels. 85

I claim:

1. The combination with the pedestal jaws of a locomotive frame; of a driving box in the jaws having a transverse dimension throughout its entire length which is not 90 greater than the distance between the jaws, and means for locking the box between the jaws against lengthwise withdrawal.

2. The combination with the pedestal jaws of a locomotive frame; of a driving box in 95 the jaws having a transverse dimension throughout its entire length which is not greater than the distance between the jaws, and retaining means for the box between its ends and the jaws, said means having out- 100 turned end flanges engageable respectively with the box and the jaws.

3. The combination with the pedestal jaws of a locomotive frame; of a driving box in 105 the jaws having a transverse dimension throughout its entire length which is not greater than the distance between the jaws, and retaining means for the box between its ends and the jaws, said means having out- 110 turned end flanges engageable respectively

with the box and the jaws, and the box having outturned end flanges engaging one end of the retaining means.

4. The combination with the pedestal jaws of a locomotive frame; of a driving box in the jaws and having outturned flanges at its outer end, a wedge and a shoe fitting between the jaws and the ends of the box, said wedge and the shoe having oppositely directed end flanges, the flanges at one end engaging the box and at the other end engaging the jaws, and the flanges of the box engaging one of the ends of the wedge and the shoe.
5. The combination with the pedestal jaws of a locomotive frame; of a driving box in the jaws and having outturned flanges at its

outer end, a wedge and a shoe fitting between the jaws and the ends of the box, said wedge and the shoe having oppositely directed flanges at their ends, the flanges at one end engaging the box and at the other end engaging the jaws, and the flanges of the box engaging one of the ends of the wedge and the shoe, the box having a transverse dimension throughout its entire length which is not greater than the distance between the jaws.

In testimony whereof I affix my signature in presence of two witnesses.

JAMES A. ANDERSON.
